UNITED STATES PATENT OFFICE.

ALLEN E. OSTRANDER, OF PATERSON, NEW JERSEY, ASSIGNOR TO
AMERICAN CAR & FOUNDRY COMPANY, OF ST. LOUIS, MISSOURI,
A CORPORATION OF NEW JERSEY.

END SILL FOR CARS.

No. 836,132.

Specification of Letters Patent.

Patented Nov. 20, 1906.

Application filed March 29, 1906. Serial No. 308,743.

To all whom it may concern:

Be it known that I, ALLEN E. OSTRANDER, a citizen of the United States, residing at Paterson, Passaic county, New Jersey, have 5 invented a certain new and useful Improvement in End Sills for Cars, of which the following is a full, clear, and exact description, such as will enable others skilled in the art to which it appertains to make and use the same, reference being had to the accompanying drawings, forming part of this specification, in which—

Figure 1 is an elevational view of my improved end sill, the platform-beams and center sills being shown in section. Fig. 2 is a plan view with the flooring removed, and Fig. 3 is a vertical sectional view on the line 3 3 of Fig. 2.

This invention relates to a new and useful improvement in end sills designed particularly for passenger-cars, the object being to construct the end sill in such manner that the longitudinal sills which extend under the car-body and which may be continuous 25 throughout the length of the car-body, if desired, project outwardly beyond the end sill to provide platform-supports. This arrangement produces a cantaliver construction which is exceedingly strong and light.

30 In the drawings, 1 indicates the side sills, which preferably terminate at the end sill.

2 designates the side walls of the car, riveted to the side sills, and 3 designates vertical posts whose lower ends are riveted to the side sills, said posts acting as stiffeners for the side walls of the car.

4 designates the center sills, preferably in the form of I-beams, which also, preferably, extend throughout the length of the car, said 40 center sills extending outwardly beyond the end of the car, so as to provide a support for the platform and also the draft-rigging.

5 designates the intermediate sills, preferably in the form of channels, which may or may not be continuous throughout the length 45 of the car, but which extend outwardly beyond the end sill and provide a support for the platform.

6 designates flanged diaphragm-plates riveted to the side sills and the intermediate 50 sills, said diaphragm-plates being spaced apart, as shown in Fig. 2.

7 designates similar diaphragm-plates arranged in the spaces between the center and intermediate sills, said diaphragm-plates being 55 also spaced apart.

8 is a truss member in the form of a channel whose flanges are riveted to the webs of the diaphragm-plates 6. This truss member extends continuously under the intermediate center sills, to the lower flanges of which the same is riveted, as shown in Fig. 1.

9 designates the end posts of the car-body, which posts are preferably Z-shaped or U-shaped and whose flanges are riveted to the 65 webs of the diaphragm-plates 6. These body end posts extend down between the diaphragm-plates 6 and 7, so that a very stiff end frame is provided for the car-body.

Having thus described the invention, what 70 is claimed as new, and desired to be secured by Letters Patent, is—

1. In an end-sill construction, the combination with cantaliver-beams and side sills, of diaphragms arranged between said parts, and a truss member extending under said cantaliver-beams and having its ends deflected upwardly above the lower edges of the side sills and secured to the diaphragms adjacent said side sills; substantially as described.

2. In an end-sill construction, the combination with cantaliver-beams and side sills, of diaphragms arranged between and riveted to said parts, said diaphragms being spaced 85 apart, and a flanged truss member extending under the cantaliver-beams and whose ends are arranged between the diaphragms adjacent the side sills, said ends being riveted to said diaphragms through said flanges; substantially as described.

3. In an end-sill construction for passenger-cars, the combination with cantaliver-beams and side sills, of spaced diaphragms arranged between said parts, corner-posts 95 and end framing-posts arranged between and,

riveted to said diaphragms, and a truss member arranged under the cantaliver-beams and having its ends deflected up between the diaphragms adjacent the side sills, to which diaphragms said deflected ends are riveted; substantially as described.

In testimony whereof I hereunto affix my

signature, in the presence of two witnesses, this 20th day of March, 1906.

ALLEN E. OSTRANDER.
